(57) **CLAIM**

The ornamental design for an air hose hanger for a rail way vehicle, as shown and described.

DESCRIPTION

FIG. 1 is a perspective view of an air hose hanger for a rail way vehicle showing our new design;

FIG. 2 is a right side elevational view thereof;

FIG. 3 is a rear view thereof;

FIG. 4 is a left side elevational view thereof;

FIG. 5 is a front view thereof;

FIG. 6 is a top plan view thereof;

FIG. 7 is a bottom plan view thereof; and,

FIG. 8 is an alternate perspective view of the air hose hanger shown in FIG. 1.

The broken lines in the drawings illustrate portions of the air hose hanger for a rail way vehicle and form no part of the claimed design.

1 Claim, 8 Drawing Sheets
